ERASER HOLDER

Arthur S. Dysart, Farmington, Conn.

Application May 13, 1937, Serial No. 142,410

4 Claims. (Cl. 120—36)

This invention relates primarily to mechanical pencils and more particularly to an eraser therefor.

An object of the present invention is to improve the eraser construction of a mechanical or other pencil enabling an elongated eraser to be used and successively advanced axially as it becomes worn.

One feature which enables me to accomplish the above named object is that a threaded member is mounted within the casing of the pencil and in engagement with the periphery of the eraser, there being means to rotate the eraser to cause axial movement of the eraser in either direction relative to the casing.

Another feature of importance is that an enclosing cap may be provided for the eraser extending over the end of the pencil casing, the cap being adapted to engage the eraser and provide means for rotating it relative to the casing.

With these and other objects in view the invention may include the features of construction and operation set forth in the following specification and illustrated in the accompanying drawing.

This application is a continuation in part of my copending application Serial No. 65,600, filed February 25, 1936.

In the accompanying drawing annexed hereto and forming a part of this specification, I have shown the invention embodied in a conventional form of mechanical pencil of the magazine type, but it will be understood that the invention can be otherwise embodied and that the drawing is not to be construed as defining or limiting the scope of the invention, the claims appended to this specification being relied upon for that purpose.

In the drawing:

Figure 1 is an outside longitudinal view of a mechanical pencil having the present invention applied thereto, a part being broken away to more clearly show the construction.

Fig. 2 is a fragmentary longitudinal section upon a larger scale and showing one preferred form of the invention.

Fig. 3 is a cross-sectional view taken on the plane of line 3—3 of Fig. 2.

Fig. 4 is a view similar to Fig. 2 and showing a modified form of the invention.

Fig. 5 is a side elevation partly broken away of the cap member shown in Fig. 4.

Fig. 6 is an end view of the cap member shown in Fig. 4.

Fig. 7 is a longitudinal sectional view of an

eraser having feeding means provided within a central axial hole therethrough; and

Fig. 8 is a longitudinal sectional view of a pencil eraser having positive advancing means forming a fixed part of the pencil structure.

In the above mentioned drawing there have been shown several embodiments of the invention which are now deemed preferable, but it is to be understood that changes and modifications may be made within the scope of the appended claims without departing from the spirit of the invention.

Briefly, and in its preferred aspect, the invention may include the following principal parts: First, a casing; second, an eraser of elongated form threaded within one end of the casing; and third, a member adapted to engage the eraser so that it may be rotated and thereby be advanced axially in either direction.

Referring more in detail to the figures of the drawing, and first to Figs. 1, 2 and 3, I provide a casing 10 of usual form found in mechanical pencils with an elongated eraser 11. The eraser 11 shown most clearly in Fig. 2 of the drawing is polygonal in cross section and engages a member 12 secured within the casing 10. The member 12 has a helical projection adapted to engage and cut slightly into the eraser 11 at its corners. By rotating the eraser 11 it will be advanced axially in either direction depending upon its direction of rotation. Preferably and as shown in Fig. 2, the member 12 comprises a helically coiled strip one longitudinal edge of which is bent inwardly to form a helically extending projection having two or three convolutions. The edge of this projection is sharp enough to cut into the outer surface of the eraser 11 and thus cause it to advance when rotated. As the eraser 11 is preferably hexagonal or octagonal the edge of member 12 engages the eraser more deeply at its corners than upon the sides.

To rotate the eraser 11 and also to enclose it when not in use there may be provided a cap member 13 fitting tightly over the end of the eraser and on to the end of the casing 10. In the form of cap member 13 shown in Fig. 2, there is formed a polygonal portion 14 closely fitting the outside surface of the eraser. By rotating the cap member 13 while in position on the casing 10 the eraser 11 may be advanced as much as required when it becomes worn away and requires replacement.

In Figs. 4, 5 and 6 there is provided the feeding member 12 within a casing 10 similar to corresponding parts shown in Fig. 2. The eraser 15,

- however, is modified materially by being cylindrical in form and having a non-circular central longitudinal hole 17. The cap member 16 shown in this figure is provided with a central elongated projection 18 permanently secured within and extending centrally within the member 16. This projection 18 in cross section corresponds to and is adapted to fit within the opening 17 within eraser 15.
- 10 The cap members 13 and 16 are retained in position on their erasers by contact with the surfaces of the erasers 11 and 15 respectively and also serve as rotating means therefor by the engaging surfaces of the cap members and erasers 15 being non-circular.

In Fig. 8 another embodiment of the invention is shown, this form having no cap member but being provided with positive and permanently mounted feeding or advancing means within the 20 casing for the eraser 19. A casing 10 is provided with a central threaded member 20 preferably and as shown secured to a transversely disposed disk 21 secured within the casing 10 at an intermediate point. At its inner end the eraser 19 is provided with a nut 22 threaded upon screw 20 and preferably moulded or imbedded within the eraser 19. Also the eraser 19 is provided with a central hole extending axially from end to end and of sufficient diameter to permit the screw 30 20 to freely enter.

To rotate the eraser 19 there may be rotatably mounted within the end of casing 10 an annular member or sleeve 23. The outer end of this sleeve 23 may be enlarged to form a flange 35 24 the outer surface of which may be roughened or knurled to aid in rotating it. The inner surface of the sleeve 23 lightly engages the surface of eraser 19 so that rotation of the sleeve 23 will also rotate the eraser 19.

40 The embodiment shown in Fig. 7 employs an eraser 25 having a central smooth hole 26 extending throughout its length. Secured within the casing and preferably to a disk 27 therein is a rod 28 fitting easily within the hole 26. At the 45 free end of rod 28 is a head portion 29, the peripheral portion of which is helical and of such diameter that it will cut or force its peripheral edge into the eraser. By rotating the eraser it will be advanced due to this helical contact between the eraser and head. As shown in this figure, the disk 27 may have a hole 30 therethrough. This may be provided so that in mechanical pencils of the magazine type lengths of lead may

be supplied to the magazine directly through the disk.

The member 12 and head portion 29 have been described as being sufficiently sharp to cut into the material of the erasers 15 and 25. If desired, however, the erasers, previously to assembling, may be provided with the necessary helical groove portions on the outside polygonal surface as in Fig. 2 or along the surface of hole 26 as in Fig. 7. These grooves would be cut by any appropriate means and in the edges of member 12 or head 29 would not be required to be sharp enough to cut into the erasers but would engage within the grooves previously cut therein.

I claim as my invention:

15 1. An eraser holder comprising in combination, a casing having a screw threaded portion therein, an eraser extending within an end thereof and engaging said screw threaded portion, a cap fitting over the end of said casing and eraser, and means on said cap engaging said eraser, whereby said eraser may be advanced along said screw threaded portion.

2. An eraser holder comprising in combination, a casing having a screw threaded portion therein, an eraser having a polygonal cross section extending within an end thereof and engaging said screw threaded portion, a cap fitting over the end of said casing and eraser, and means on said cap engaging the polygonal cross section of 30 said eraser, whereby said eraser may be advanced along said screw threaded portion.

3. An eraser holder comprising in combination, a cylindrical casing, an eraser extending within one end thereof, an axially extending threaded 35 member mounted centrally within said casing and retained against rotation, said eraser having a central hole extending therethrough, and a nut embedded in said eraser engaging said threaded member.

40 4. An eraser holder comprising in combination, a cylindrical casing, an eraser extending within one end thereof, an axially extending threaded member mounted centrally within said casing and retained against rotation, said eraser having a central hole extending therethrough, a nut embedded in said eraser engaging said threaded member, and a cap fitting over the end of said casing and eraser and engaging a non-circular surface thereof, whereby said eraser may be advanced along said threaded member.

ARTHUR S. DYSART.
